DESIGN FOR A SLIP

Seamon Wolf, New York, N. Y.

Application May 9, 1942, Serial No. 106,842

Term of patent 14 years

To all whom it may concern:

Be it known that I, Seamon Wolf, a citizen of the United States of America, residing in New York city, county of New York, and State of New York, have invented a new, original, and ornamental Design for a Slip, of which the following is a specification, reference being had to the accompanying drawing, forming part thereof, wherein,

The characteristic feature of my design resides in the combination on the slip disclosed of the specific, shaped contrasting trim around the top, in association with the matching contrasting trim at the front waist line, all as shown.

I claim:

The ornamental design for a slip, substantially as shown, and described.

SEMON WOLF.
